IMPROVEMENT IN CAMERAS.

W. H. MASTERS, OF PRINCETON, ILLINOIS.

Letters Patent No. 59,917, dated November 20, 1866.

SPECIFICATION.

TO ALL WHOM IT MAY CONCERN:

Be it known that I, W. H. MASTERS, of Princeton, Bureau county, and State of Illinois, have invented a new and useful Improvement in Solar Cameras; and I do hereby declare that the following is a full, clear, and exact description thereof, which will enable others skilled in the art to make and use the same, reference being had to the accompanying drawing forming part of this specification, in which—

Figure 1 represents a side elevation of this invention, partly in section.

Figure 2 is a longitudinal vertical section of the same, the line x x , fig. 3, indicating the plane of section.

Figure 3 is a horizontal section of the same, taken in the plane indicated by the line y y , fig. 2.

Similar letters of reference indicate like parts.

This invention relates to a solar camera for printing photographic pictures, and for other purposes, which is provided with suitable gear whereby the same can be set to correspond to the position of the sun at any moment, so that the full benefit of the sun's rays is obtained, and clear and distinct pictures can be produced in a comparatively short time. A conical shield close behind the condensing lens in the mouth of the upper chamber of the camera box, in combination with a diaphragm in front of the small lens, prevents the rays of light from being concentrated on any portion of the wood-work, and thereby the box is rendered comparatively fire-proof. The lower or printing chamber is supplied with cleats on the upper and lower sides, which form the guides for the paper screen, and keep the same in place while the printing is going on, and the negative-holder is composed of three distinct frames, which allow of adjusting the negative in the proper focus with the greatest ease and facility.

A represents a stand made of wood or any other suitable material, from which rise two uprights, B, which are held in position by a brace, C. The upper ends of the uprights B form the bearings for a screw rod, a, which passes through ears or branches, b, secured to the under surface of a disk, c. This disk is held in an inclined position by means of a screw, d, passing through an arm, which projects from its periphery, and it is provided with cogs extending partially or wholly round its circumference. Disk c is to be put into position with its plane parallel to the equator, and pivot f parallel to the poles of the earth, and, in the same latitude, never needs readjusting after once being put into position. Thus, if the camera is adjusted for use at the equator, the disk c is required to be in a perpendicular position; at the poles the position would necessarily be horizontal; and at any intermediate latitude the disk c is inclined in proportion to the degree of latitude where used. For instance, at New Orleans, a latitude of 30° , the inclination of the disk will be 30° , while at St. Paul, a latitude of 45° , the inclination will be 45° from perpendicular, the degree of latitude always indicating the degree of inclination of the disk. Therefore it is only in reference to the degree of latitude of the locality where used that the disk c ever requires to be readjusted. I do not confine myself to the above gearing for the rotary motion, as the pinion g may be secured to the disk, and plate e be supplied with cogs, instead of the disk c. On the disk c rests a plate, e, which is connected with the same by a central pivot or polar axis, f, and is made to revolve by the action of a pinion, g, which gears in the cogs of the disk c. Said pinion is mounted on a shaft, h, which has its bearings in a cage, i, secured to the plate e, and a hand-wheel, f, serves to impart to it the required rotary motion. From the plate e rise two lugs or ears, j, which form the bearings for the pivot k, that supports the box D, as shown in figs. 1 and 2 of the drawing, said box being provided with a suitable bracket, l, through the ears of which the pivot k passes, so that the box D is free to swing up and down in a vertical plane. In order to adjust the box in the desired inclination, a segmental arm, m, extends from the plate e, the edge of which is provided with cogs which gear in an endless screw, n. This screw has its bearings in a lug, o, on the inner surface of the lower box or printing chamber, and in a plate, p*, at its bottom, and it is provided with a head, o*, so that said screw can be turned conveniently in either direction. By the action of the pinion g, and disk c, the box D can be revolved in an equatorial plane; and by the screw n, and segmental arm m, it can be moved in a vertical plane, and its position can thus be adjusted with the greatest ease and convenience. The box D is divided in two compartments, p q. The compartment p, which forms the printing chamber, and which is somewhat larger than the compartment q, is provided with strips, r, on top and bottom which form the guides for the paper shield, s. The compartment q contains the lenses t u, one at or near its mouth, and the other at some distance from the first, as clearly

shown in figs. 2 and 3. The large lens, *t*, serves to collect the rays of the sun, and to concentrate the same in the axis or central part of the small lens, *u*, by which they are spread on the paper, which is fastened on the shield *s*. In order to prevent the rays or any portion of them from being concentrated on some portion of the wood-work, and to set fire to the same, I have applied a conical shield, *v*, close behind the large lens *t*, and a diaphragm *w*, of metal or other suitable non-combustible material, close in front of the small lens *u*, the shield *v* being so shaped that it prevents any of the rays from going astray. Between the two lenses *t* and *u* is the negative-holder *E*, which is composed of three distinct frames, *a' b' c'*. The frame *a'* is secured to a slide *a**, which straddles the top of the compartment *g*, which is provided with a set-screw *d'* that serves to fasten the same in any desired position, and also to move it up and down in the direction of the longitudinal axis of the box *D*. The frame *b'* is fitted into dove-tailed guide-ways in the frame *a'*, and it is so arranged that it can be moved in a transverse direction; and the frame *c'* is fitted into dove-tailed guide-ways in the frame *b*, and the direction in which it can be moved is up and down, and at right angles to the direction in which the frame *b'* moves. Suitable friction-springs, attached to the edges of the frames *b' c'*, keep the same in the desired position. The negative is secured to the frame *c'*, and by the constant action of the three frames, *a' b' c'*, said negative can be readily adjusted in the proper position in relation to the lenses *t u*. By this arrangement I am enabled to print clear and distinct pictures of different size from negatives, and the operation of my box is so simple that it can be readily understood by persons of ordinary mechanical skill, since, when the instrument is adjusted according to the declination of the sun, and the disk *c* gives the plate *e* a rotary motion corresponding with that of the earth, the box may be made to follow the path of the sun during the printing by a single motion obtained by pinion *g*, after having adjusted the vertical motion by endless screw *n*, at the beginning of each day.

To put the camera in position, the operator has only to level the stand with the cross till pointing east and west, raise or lower the inclination of the disk *c* by means of the screw-rod until the desired inclination is obtained, bringing its plane parallel to the equator, and when thus adjusted pivot *f* is always parallel to the poles of the earth; thus we have a correct basis for the rotary motion. Then the instrument may be adjusted in its vertical movement by means of the endless screw *n*, acting upon the segmental arm *m*, without disturbing the position of the disk *c* and pivot *f*; and when properly adjusted according to the above directions the box *D* is made to point to the sun at any day in the year, or any hour of the day. Then, by rotating the camera by means of the hand-wheel, the camera may be made to follow the path of the sun correctly all day, no matter what the inclination of the sun may be to the earth's plane, and by turning the endless screw each morning a very little, the vertical adjustment is secured for the day; thus the sun may be followed for a year without interrupting the position of disk *c* and pivot *f*, as before stated.

What I claim as new, and desire to secure by Letters Patent, is—

The shielding cone *v*, and diaphragm *w*, between the lenses *t u*, substantially as and for the purposes set forth.

W. H. MASTERS.
